ANTIFREEZING CONNECTION FOR TANKS AND REGULATORS

Filed Dec. 29, 1921

Fig. 3

John Harris Inventor
By Hull, Brock & West,
Atlys.

UNITED STATES PATENT OFFICE.

JOHN HARRIS, OF CLEVELAND, OHIO, ASSIGNOR TO THE HARRIS CALORIFIC COMPANY,
OF CLEVELAND, OHIO, A CORPORATION OF OHIO.

ANTIFREEZING CONNECTION FOR TANKS AND REGULATORS.

Application filed December 29, 1921. Serial No. 525,618.

This invention relates to the tanks and regulators employed with gases, and more particularly to tanks and regulators of the type used in connection with oxygen and the combustible gases employed for the cutting and welding of metal. In the operation of regulators with such gases, considerable annoyance and delay in operation have been caused by the freezing of the regulator connections and the parts of the regulator, due to the sudden expansion of the gases when liberated from their tanks or cylinders.

It is the object of this invention to prevent this freezing operation and to accomplish the same in a most efficient manner and in and through the use of a connection which is particularly simple in construction and economical of production. In the drawings, I have shown my invention in connection with a tank and regulator of ordinary standard construction, Fig. 1 representing in elevation a portion of a supply tank and a regulator adapted to communicate with said tank through my connection; Fig. 2 an enlarged longitudinal sectional view through my connection and the parts associated therewith; and Fig. 3 a sectional view corresponding to the line 3—3 of Fig. 2.

Describing by reference characters the various parts illustrated herein, 1 denotes a supply tank for the gas, the pressure whereof is to be regulated. This tank is provided at its upper end with the usual valve 2 and valve casing 2^a whereby the flow of gas from the tank to the outlet connection 3 through the said casing may be controlled or cut off, as desired. The outer end of the connection 3 is threaded for the reception of a gland nut 4 having a flange or shoulder 4^a which is adapted to engage a flange or shoulder 5^a upon a nipple 5 having a rounded end 5^b adapted to seat against the correspondingly shaped end (not shown) of the connection 3. The nipple 5 is provided with a bore 5^c adapted to register with the bore of the nipple and to discharge at its outer end into my connection, the body of which is indicated at 6, said connection being threaded upon the adjacent end of the nipple and being provided at such end with a threaded

chamber 6^a for the reception of the threaded end of the nipple, said chamber communicating with the bore 5^c and with a bore 6^b, 6^c, extending through the said connection and communicating with the receiving chamber 7^a of the regulator 7, which regulator may be of any standard construction.

The connection 6 is preferably somewhat longer than the connections usually employed between tanks and their regulators and is provided with temperature equalizing ribs 6^d projecting therefrom, these ribs being preferably formed as integral rings or collars projecting from the exterior surface of the connection and being spaced apart.

In operation, the valve 2 will be opened in the usual manner to permit gas from the cylinder or tank 1 to pass into the connection 3, nipple 5, connection 6, and regulator 7. It will be noted that the bore section 6^b is of greater diameter than the bores 5^c and bore section 6^c, whereby some expansion is permitted to the gases entering the first mentioned bore section. This preliminary expansion results in an absorption of heat by the expanded gas from the connection 6, but freezing and solidification is prevented by the ribs or flanges 6, which serve as temperature equalizers to prevent too rapid absorption of heat by the expanded gases from such connection and the consequent detrimental lowering of the temperature of the body of the connection and of the gas therewithin. The gas, thus partly expanded, is conducted into the receiving chamber 7^a of the regulator and, because of the action of the temperature-equalizing connection 6, will not cause freezing of the parts of the regulator by reason of the further expansion of the gas within such chamber.

Having thus described my invention, what I claim is:

The combination with a gas tank having a valve controlled outlet, of a regulator, a relatively short rigid connection interposed between said outlet and regulator and having sufficient rigidity to sustain the weight of the regulator and its associated parts, said connection comprising an annular member having an enlarged receiving por-

tion and a restricted discharge portion, the receiving end of said connection being threaded for the reception of a gland nut for connecting the same with said gas tank, the opposite end of said connection being adapted for connection with said regulator, said connection having a plurality of tem- perature equalizing ribs projecting from the exterior surface thereof thereby to neutralize the cooling effect due to the expansion of 10 the gas flowing through said connection. In testimony whereof, I hereunto affix my signature.

JOHN HARRIS.
